UNITED STATES PATENT OFFICE.

JOHN L. MOHUN, OF BROOKLYN, NEW YORK.

CAR-ROOF CONSTRUCTION.

1,069,565.

Specification of Letters Patent.

Patented Aug. 5, 1913.

Application filed July 28, 1911. Serial No. 441,086.

To all whom it may concern:

Be it known that I, JOHN L. MOHUN, a citizen of the United States, residing at Brooklyn, in the county of Kings and State of New York, have invented new and useful improvements in Car-Roof Construction, of which the following is a specification.

This invention relates to a car roof construction, and more particularly to flexible metallic roofs for freight cars, such as shown and described in my prior application Ser. No. 629,960, filed May 27, 1911.

One of the objects of my present improvement is to prevent any leakage at the point of fastening of the roof to the side plates of the car, and for this purpose I provide an improved form of bolt connection which not only prevents leakage, but also prevents the bolt from becoming loose.

Another object is to provide an improved roof lining to serve as an insulation against heat and prevent high temperatures within the car.

Another object is to provide improved means for fastening the purlins to the metal carlines; and still another object is to provide an improved form of carline cap for covering the carline and the turned over edges of the metal roofing sheets.

In the accompanying drawings: Figure 1 is a transverse section of a portion of a car roof, showing my improved heat insulating lining suspended from the carline; Fig. 2, a transverse section of the car roof at the side plate of the car, showing my improved fastening means for the carline hood and roofing sheets; Fig. 3, a similar section taken between carlines and showing my improved bolt connection for fastening the roofing sheets; Figs. 4 and 5, a plan and side view respectively, showing my improved means for fastening the purlins to the carlines; Fig. 6, a transverse section of a carline and carline cap, showing the edges of the roofing sheets; Fig. 7, a similar view of the ridge pole and ridge cap; and Figs. 8 and 9, similar views of a carline and a ridge pole, respectively, showing a modification in the roofing sheets and the caps.

As set forth in my prior applications, the

roof construction, in general, is composed of metal carlines, 20, formed of U shaped pressed steel sections, which extend across the car from one side plate to the other, and carry metal purlins, 24, and a metal ridge pole, 25, which, together with the carlines support the metal roofing sheets, 23. The edges of the roofing sheets are supported over the channels in the carlines and in the ridge pole, and are covered by carline caps, 22, and ridge caps, 33, while the lower edge is bent down over the side plate, 21, and facia board, 58, the sheets being fastened to the side plates.

According to one of the features of my present improvement, I provide a bolt, 68, for fastening the roofing sheets to the side plate and having a rigid or integral collar or flange, 69, which is located between the roofing sheet and the side plate around the hole through which the bolt passes and thereby prevents any rain water from passing in around the bolt and leaking into the car. The end of the bolt then passes through the turned down edge of the roofing sheet, 75 which may be clamped tightly against the outside of the collar by means of a nut, 70, and the inside of the collar may be drawn tightly against the side plate by a nut upon the inside end of the bolt, as shown in Fig. 3. This makes a tight joint which completely excludes moisture and at the same time prevents loss of the bolts, for even if the outside nut should come off, the bolt is still firmly held in position by the flange and inside nut, 85 and if the inside nut should come off, the bolt is still held in place by the roofing sheet, which is held by other bolts, so that it is practically impossible that any of the bolts should become loose or be accidentally lost.

Fig. 2 shows the arrangement of the fastening at the carline where the bolt, 68, passes not only through the roofing sheet and side plate, but also through the flange 95 of the carline, 20, and the carline hood, 60. In this case the outside nut, 70, clamps the flange of the hood, and the roofing sheet against the collar, 69, of the bolt, and the inside nut draws the bolt and collar tightly 100.

against the side plate and the carline flange which is preferably seated in the side plate flush with its outer surface.

For the purpose of keeping down the temperature of the interior of the car in warm climates where considerable heat may be radiated inward from the outside metallic roof, I provide an insulating lining preferably composed of boards, 72, forming an inside ceiling for the car, and carried by cross beams or rafters, 71, which are supported at their ends on blocks, 74, secured to the side plates, 21, and at the middle or intermediate points, by hangers, 73, attached at their upper ends to the carline, 20. This forms an air space between the ceiling or lining and the outside metal roof of the car, and effectually prevents the radiation of a great amount of heat through to the interior of the car.

In order to fasten the purlins to the carlines, and key the structure together at these points, the purlin, 24, may be notched, and a metal strap 24^a, fitted over the notched portion of the purlin and bolted to the carline, 20, as indicated in Figs. 4 and 5. The strap may be of substantially the same width as the channel in the carline, and fitted thereto so as to effectually key the structure together at this point.

Another feature of my present improvement relates to the shape or configuration of the edges of the roofing sheets and the carline caps and ridge caps coöperating therewith. As shown in Figs. 6 and 7, the edges of the roofing sheets are folded over and down nearly flat, while the side edges of the caps, 22 and 23, may be folded inward to a substantially horizontal position; the folded edges of the roofing sheets and caps being hooked together or interlocked, so as to slide within each other and form a close joint with a very tortuous passage for the admission of moisture or cinders which might be driven in under the cap members. The folded edges of the cap members are rounded to form loops, which serve as strengthening ribs and contain cavities, 22^b, in the carline caps, and 33^b, on the ridge cap to provide sufficient space for clearance and for the collection of the very small amount of cinders or other foreign matter, which might possibly pass around the interlocked edges of the sheets. With this form of joint, the sheets are slidably supported with respect to the supporting members, and the caps, and the entrance of cinders into the channels in the carline and ridge pole with the moisture is prevented.

According to the modification shown in Figs. 8 and 9, the edges of the roofing sheets are turned up, then over and down substantially vertically, over the channel in the car-

line, 20, or in the ridge pole, 25, and the carline cap, 22^a, and the ridge cap, 33^a, are in the form of inverted channels covering said up-turned edges of the roofing sheets. In this case the turned up edges prevent the entrance of cinders into the carlines and ridge pole, and any water or moisture which passes over said up-turned portion drains into the channel in the carline or ridge pole. This form of turned up edge also serves to stiffen the roofing sheets, and renders them more durable.

Having now described my invention, what I claim as new, and desire to secure by Letters Patent, is:

1. In a car roof, the combination with an outside metal roofing sheet bent down over the side plate of the car, of a fastening bolt passing through said sheet and side plate and having an integral collar between the side plate and said roofing sheet.

2. In a car roof, the combination with an outside metal roofing sheet bent down over the side plate of the car, of a fastening bolt passing through said sheet and side plate and having an integral collar between the side plate and said roofing sheet, means for fastening the bolt to the side plate, and a nut on said bolt outside of the roofing sheet.

3. In a car roof, the combination with an outside metal roofing member extending down over the side plate of the car, of a fastening bolt passing through said member and side plate and having a collar between the side plate and said roofing member and making a water tight joint on the bolt.

4. In a car roof, the combination with metal carlines having drain channels and outside metal roofing sheets supported thereon, of transverse rafters, hangers attached to the walls of the carlines above the bottom of said drain channels for suspending the rafters from the carlines, and an insulating ceiling carried by said rafters.

5. In a car roof, the combination with a U-shaped metal carline, of a notched purlin supported thereon, and strap passing over the notched portion of the purlin and secured to the carline.

6. In a car roof, the combination with a U-shaped metal carline having a depressed seat for a purlin, of a purlin having a notch opposite the channel of the carline, and a strap passing over the notched portion of the purlin and secured within the channel of the carline.

7. In a car roof, the combination with a metal carline, of metal roofing sheets supported thereon, and having their edges folded over and a metal cap for said carline covering the edges of the roofing sheets and having its edge folded under in an upwardly rounded loop forming an oval cavity

within the fold and slidably engaging and interlocking with the turned over edges of the roofing sheets.

8. In a car roof, the combination with a metal ridge pole, of metal roofing sheets supported thereon at their upper edges and having said edges folded over, and a ridge cap covering said upper edge of the roofing

sheets and having its edge folded under with an upwardly rounded loop and interlocking with the edges of the roofing sheets. 10
